FLUORESCENT LAMP

Dan M. Andre, 8843 Kostner Terrace, Skokie, Ill. 60076

Filed Nov. 25, 1966, Ser. No. 4,801

Term of patent 3½ years

(Cl. D48—20)

FIG. 1 is a front perspective view of a fluorescent lamp illustrating my new design, with the standard supporting arm and the lamp shade on the base in phantom outline.

FIG. 2 is a side elevational view of the same. The elevational view of the lamp from the side opposite that shown in this view is identical.

FIG. 3 is a front elevational view of the same.

FIG. 4 is a top plan view of the same.

FIG. 5 is a fragmentary rear elevational view showing a piece of said lamp.

The dominant features of my design reside in the portions shown in full lines. The support arm has been fragmentarily shown in FIGURES 4 and 5 for convenience of illustration.

I claim:

The ornamental design for a fluorescent lamp, substantially as shown and described.
